(57) **CLAIM**

The ornamental design for a watch pendant, as shown and described.

DESCRIPTION

FIG. 1 is a front elevational view of a watch pendant showing my new design, with the front cover rotated to an open position;

FIG. 2 is a back elevational view thereof;

FIG. 3 is a top plan view thereof;

FIG. 4 is a bottom plan view thereof;

FIG. 5 is a left side elevational thereof;

FIG. 6 is a right side elevational view thereof;

FIG. 7 is a front, right side perspective view thereof;

FIG. 8 is a back, left side perspective view thereof; and,

FIG. 9 is a front elevational view of the watch pendant, with the front cover rotated to an alternate closed position.

1 Claim, 9 Drawing Sheets
